(57) **CLAIM**

The ornamental design for a drill with pivotable drill head, as shown and described.

DESCRIPTION

FIG. 1 is a left front perspective view of a drill with pivotable drill head showing my new design.

FIG. 2 is a right front perspective view of FIG. 1.

FIG. 3 is a rear perspective view of FIG. 1.

FIG. 4 is a left side elevational view of FIG. 1.

FIG. 5 is a right side elevational view of FIG. 1.

FIG. 6 is a front elevational view of FIG. 1.

FIG. 7 is a rear elevational view of FIG. 1.

FIG. 8 is a top plan view of FIG. 1.

FIG. 9 is a bottom plan view of FIG. 1.

FIG. 10 is a front perspective view in which the head is pivoted 135°.

FIG. 11 is a left side elevational view of FIG. 10.

FIG. 12 is a front perspective view in which the head is pivoted 180°.

FIG. 13 is a left side elevational view of FIG. 12.

FIG. 14 is a front perspective view in which the head is pivoted 135° to rear of handle.

FIG. 15 is a left side elevational view of FIG. 14.

FIG. 16 is a front perspective view in which the head is pivoted 90° to rear of handle; and,

FIG. 17 is a left side elevational view of FIG. 16.
